UNITED STATES PATENT OFFICE.

EDWARD L. BRADLEY, OF SAN FRANCISCO, CALIFORNIA.

DESIGN FOR A DISPLAY EASEL.

Application filed February 23, 1929. Serial No. 30,191. Term of patent 7 years.

To all whom it may concern:

Be it known that I, EDWARD L. BRADLEY, a citizen of the United States, and a resident of the city and county of San Francisco, State of California, have invented a new and original Design for a Display Easel, of which the following is a specification, reference being had to the accompanying drawings, forming part thereof.

In the drawings:

Fig. 1 is a perspective of the front of the display easel showing my new design.

Fig. 2 is a perspective of the back of the display easel.

I claim:

The ornamental design for a display easel as shown.

EDWARD L. BRADLEY.
